HOMOGENIZER

Mead Cornell, Dayton, Ohio, assignor to The Cornell Machine Company, Cleveland, Ohio, a corporation of Ohio

Application June 28, 1935, Serial No. 28,925

22 Claims. (Cl. 259—96)

This invention relates to a homogenizer and is designed primarily for effecting an intimate and substantially permanent mixture of two or more fluids which normally are wholly or partially immiscible. Such fluids can be united or blended only with great difficulty and then usually with the sacrifice of some desirable characteristic or quality of the fluids. For example, in the preparation of lubricating oils it is customary to blend two or more oils of different densities and heretofore it has been customary to place the oils in the container and heat the same to relatively high temperature, and to agitate the same by stirring or passing air through the heated mass for a long period of time. This is not only a slow and expensive procedure, requiring the installation of costly equipment, but it results in the discoloration of the oils and more or less oxidization of the same, both of which are highly undesirable.

One object of the present invention is to provide a method for effecting an intimate and substantially permanent mixture of a plurality of fluids which normally are wholly or partially immiscible, without the deterioration of the fluid or the imparting of undesirable characteristics thereto.

A further object of the invention is to provide such a method which can be performed mechanically and without the use of heat.

A further object of the invention is to provide such a method which may be performed continuously and will have a high rate of production.

A further object of the invention is to provide an efficient apparatus for carrying out the method.

A further object of the invention is to provide such an apparatus in which the mixing of the fluids may be effected in a partial vacuum.

A further object of the invention is to provide such an apparatus which will be simple in its construction and which may be installed and operated at low cost.

Other objects of the invention may appear as the method and apparatus are described in detail.

In the accompanying drawings Fig. 1 is a vertical sectional view taken centrally through an apparatus embodying my invention and partly broken away; Fig. 2 is a top plan view of such an apparatus, partly broken away; Fig. 3 is a sectional detail view of a portion of the film forming device, on an enlarged scale; and Fig. 4 is a detail view of the feed controlling valve.

In homogenizing a plurality of fluids in ac-

cordance with my method the several fluids are mingled one with the other and the mingled mass of fluid is delivered to a device, such as a centrifugal disk, from which it is projected in the form of a thin continuous film. The film will maintain its continuity for some distance beyond the edge of the projecting device, and is caused to contact with a deflector which will deflect it against a stationary surface, such as the wall of a receptacle within which the centrifugal disk operates. The action of the deflector will also retard and slightly thicken the film so as to increase the body thereof and cause it to retain its continuity until it impinges against the wall. The film strikes the wall at an acute angle so that its continuity is not interrupted and flows down that wall in the form of a film to the body of liquid in the receptacle. In this manner the fluids are not only very intimately mixed but they are not broken up, or sprayed, and oxidization is greatly reduced. Where desired the oxidization may be further reduced by exhausting the air from the receptacle in which the operation is performed.

In the accompanying drawings I have illustrated one form of apparatus for performing my method but it will be understood that this particular embodiment has been chosen for the purpose of illustration only and that the apparatus may take various forms, for the purpose of adapting the same to liquids of different kinds or for other reasons. The method and apparatus may be employed for mixing fluid or semi-fluid substances of various kinds, or for mixing one or more fluids with one or more finely divided dry substances which may be fed to and mingled with fluids, and the term "fluid" as herein used is intended to include any such substance.

The particular apparatus here illustrated comprises a housing 5 which encloses the film forming apparatus and constitutes a receptacle for the mixed fluids. A supporting structure 6 is arranged near the upper end of the housing or receptacle 5 and, in the present instance, forms a closure for that receptacle. This supporting structure is provided with a central opening 7 through which extends a vertical shaft 8. To the lower end of this shaft is rigidly secured a centrifugal disk 9 and the outer end of the shaft is connected with a suitable driving mechanism. As here shown, the shaft 8 is a continuation of the shaft of a motor 10 which is mounted on the structure 6. The shaft is journaled in a suitable bearing 11 arranged within the opening 7 in the supporting structure. In the present instance

the supporting structure or closure 6 is secured to the receptacle with a hermetically sealed joint and the space about the shaft 8 within the opening 7 is sealed by a suitable packing, such as a 5 cup leather 12.

The disk 9 is of such a character that when rotating at high speed the fluids delivered to the upper surface thereof near its center will be caused to move over the surface of the disk and 10 to be projected from the outer edge thereof in the form of a film. In the present instance, the outer portion 13 of the upper surface of the disk is inclined upwardly and outwardly with relation to a plane of rotation of the disk so that as the 15 fluids are thrown outwardly by centrifugal force they will be retained in contact with this inclined surface, that is, will be prevented from moving over the same in the form of drops or bubbles, and will be projected from the edge of the disk 20 in the form of a film of extreme thinness. Preferably the inner portion of the upper surface of the disk is depressed as shown at 14 to form an annular recess arranged about the hub 15 of the disk and the wall of this recess merges gradually 25 into the inclined surface 13. The fluids are delivered into this recess and are forced out of the same onto the inclined surface thus preventing any large body of fluid from moving over the inclined surface and causing the fluids to spread 30 over the inclined surface and form a thin continuous film which is subsequently projected from the edge of the disk.

The several fluids which are to be mixed may 35 be delivered to the central portion of the disk in any suitable manner but I prefer to first mingle the several fluids one with the other and then deliver the mingled mass into the recess 14 of the disk. In the present construction, the supporting structure, or closure, 6 is provided with a 40 conduit 16 adapted to be connected with the manifold 17 through which the mingled fluids are supplied thereto. The conduit 16 communicates with an annular conduit 18 also formed in the supporting structure, or closure, and extending 45 about the opening 7 in the structure. The supporting structure is also provided with an annular flange 19 extending downwardly therefrom about the hub 15 of the disk and spaced from that hub to form a passageway through which 50 the fluids may be delivered to the recess 14, and the lower edge of the flange 19 preferably extending into the recess. The annular conduit 18 is connected with the passageway formed within the flange 19 by a series of openings 20 spaced 55 about the inner wall of the conduit so that the mingled fluids will be delivered in substantially equal quantities to the passageway on all sides of the shaft 8. For the purpose of retarding the flow of the fluids from the annular conduit 18 to the passageway and thereby securing a very uniform distribution of the same I have mounted within the opening 7 and about the bearing 11 a sleeve 21 which projects across the openings 20 and has its lower edge adjacent to and spaced a short distance from the inner surface of the flange 19.

It may sometimes be desirable to arrange above 70 the inner portion of the disk a guard or deflector plate which will prevent the fluid from rising above the surface of the disk and moving outwardly without contacting with the inclined outer surface thereof which, of course, would prevent the fluid from being spread into film form and projected from the disk in the desired manner. 75 For this purpose I have mounted above the inner

portion of the disk a guard comprising a deflector plate 22 and a hub 23 which, in the present instance, is mounted upon the annular flange 19 for both rotatory movement and vertical movement with relation thereto. The guard thus surrounds the inlet passageway formed within the flange 19 and the outer edge of the annular deflector plate is supported adjacent to the inclined surface of the disk. The downward movement of the guard is limited by a suitable retaining device, such as a stop ring 24, which is so arranged as to permit the outer edge of the deflector plate to contact with the surface of the disk when the apparatus is idle or when no fluid is being delivered to the disk. When rotation is 10 imparted to the disk the contact of the latter with the deflector plate will cause the guard to rotate with the disk and when fluid is delivered to the disk and accumulates beneath the deflector plate it will raise the latter out of contact with 15 the disk to permit the fluid to pass to the outer portion of the inclined surface of the plate but will deflect the fluid into direct contact with the surface of the disk. The deflector plate rests upon the body of fluid on the inner portion of 20 the disk and will be caused to rotate about the flange 19 but at a speed somewhat less than the speed of rotation of the disk, the speed of rotation of the deflector plate depending in part at least upon the viscosity of the fluid and the quantity passing between the deflector and the disk. 25 The mass of fluid beneath the deflector plate is thus confined between two surfaces rotating at different speeds which act thereon somewhat in the manner of a colloidal mill and causes a mingling of the different fluids. While this guard is shown as applied to the particular disk here illustrated it will be obvious that it will operate in the same manner with a disk having its upper inclined surface extending in a straight line to 30 the hub thereof.

Mounted about the centrifugal disk 9 is a deflector ring 25 having a lower contact surface 26 arranged in the path of the film discharged from the disk and spaced such a distance from the disk 45 that the film will impinge against the contact surface before it has had an opportunity to disintegrate or break up into drops or spray. This contact surface is arranged at an acute angle to the path of the film as it is discharged from the disk 50 and also at an acute angle to the wall of the receptacle 5. In the arrangement shown the contact surface has its outer portion curved downwardly, as shown at 27, so that the fluid which is deflected thereby will impinge against the inner 55 surface of the receptacle wall at a sharp angle. The contact of the film with the deflector will retard the movement of the film and slightly thicken the same so as to increase the body of the film 60 sufficiently to maintain the continuity thereof until it has impinged against the wall of the receptacle and the film will then flow down the wall of the receptacle, while in film form, into the body of fluid in the lower portion of the receptacle. In this manner the several fluids are not only very 65 intimately mixed one with the other but by maintaining the fluids in the form of a continuous film throughout their travel from the disk to the receptacle the tendency of the fluids to oxidize is very much less than would be the case if the 70 fluids were broken up and discharged in the form of drops or a spray.

The distance which the contact surface of the deflector is spaced from the edge of the disk and its angle with relation thereto depends in 75

part upon the character of the fluids under treatment, as some fluids may be maintained in film form for a much greater distance than others. Therefore, to accommodate the device to fluids of various kinds the deflector ring 25 is made adjustable so as to vary both the distance between the contact surface thereof and the edge of the disk and the angle of incidence of the film with relation to the contact surface. This adjustment may be secured in any suitable manner but, as here shown, the ring is supported from the structure or closure 6 by means of screws 28 which are extended through nuts 29 mounted in the supporting structure and held against axial movement with relation thereto. By rotating these nuts the screws and the deflector ring may be caused to move vertically. In some cases it is desirable to effect the mixing or homogenizing of the fluids in a partial vacuum, as will be hereafter explained, and I have therefore provided means for tightly sealing the space about the screws 28 and nuts 29. For this purpose a dome-shaped cap 30 is mounted about each nut and has in its upper end an opening 31 through which the screw 28 extends, the cap being provided with a curved seat surrounding the opening. The joint between the lower edge of the cap and the supporting structure is hermetically sealed, as by interposing a suitable sealing medium 32 between the parts. A clamping nut 33 is mounted on the upper end of the screw above the cap 30 and has its lower portion of semi-spherical shape, as shown at 34, to engage the seat surrounding the opening 31 in the cap and to form an air tight joint therewith. The opening through the clamping nut is closed at its upper end, as shown at 35, this upper portion being of sufficient length to permit of the necessary movement of the nut with relation to the screw. Hence it will be apparent that when the clamping nut is tightened down against the cap 30 the joints at 31 and 32 will be tightly sealed and no air can enter the receptacle about the screw. When the deflector ring is to be adjusted the clamping nut and cap are removed and a wrench applied to the outer portion of the adjusting nut 29.

As above stated the fluids to be mixed may be supplied to the film forming device in any suitable manner but I prefer to supply the same through a single conduit or manifold such as shown at 17. In the arrangement shown this manifold has connected therewith a plurality of branch pipes 36 and each of these pipes leads to a pump, one of which is shown at 37. The intake of each pump is connected by a pipe 38 with a source of supply for one of the fluids to be mixed. Each pump is of a variable discharge type so that the amount of fluid delivered by each pump may be controlled by the operator in order to secure the proper proportions of the several fluids as delivered to the homogenizer. The variable discharge may be effected in any suitable or well known manner, as by any of the well known volume controls or by varying the speed of operation. In the present instance the several pumps are driven at a constant uniform speed and to this end they have driving connection with a single shaft 39 driven by an electric motor 40. The manifold may have any suitable number of branch pipes 36 and preferably it is provided with several of these branches, say six, although only three are here shown, thus enabling the apparatus to be used

with any desired number of fluids within the range of the manifold, it being understood, of course, that any one or more of the pumps may be rendered inoperative when not needed. The several fluids which are discharged by the respective pumps are mingled one with the other in the manifold 17 and flow together into the manifold 16 of the closure. In order to secure a uniform feed of the mingled fluids to the homogenizer the manifold is provided with a feed controlling valve 41 interposed between the innermost branch pipe 36 and the conduit 16, this valve being of such a character as to maintain a constant pressure or head against which the pumps must operate and therefore causing the uniform operation of the same. Its use is particularly desirable when a partial vacuum is maintained within the receptacle 5 which, under certain circumstances might tend to reduce the pressure head and thus vary the operation of the pumps, but it also serves to maintain this constant pressure head whether the blending is effected in a vacuum or otherwise. As here shown, this valve comprises a valve disk 42 opposed to the flow of the fluid in the manifold 17 and pressed against its seat by a spring 43. The outer end of this spring is engaged by a head 44 on a screw 45 which enables the resistance of the spring to the flow of fluid to be regulated and also enables the valve to be closed by a sufficient tightening down of the screw 45. In operation the tension of the valve spring is adjusted according to the pressure head it is desired to maintain and the pressure of the fluid will force the valve disk 42 from its seat sufficient to permit the desired flow of fluid but the tension of the spring will limit the extent of movement of the disk.

In the treatment of certain fluids, particularly oils, it is desirable to entirely prevent oxidation if possible and for this purpose the present apparatus is of such a character that the homogenization of the fluids may be effected in a partial vacuum. As has been explained the receptacle 5 in which the centrifugal disk operates is hermetically sealed. The receptacle is provided at its lower end with an outlet 46 which is connected with a conduit 47 extending into a second receptacle or housing 48 which constitutes a vacuum chamber. The conduit 47 extends upwardly to a point near the top of the vacuum chamber and is there provided with a spreader 49, here shown as an annular flange extending from the upper edge of the conduit 47 to a point near the cylindrical wall of the receptacle 48. This annular flange slopes downwardly from the upper end of the conduit toward the wall of the receptacle so that it has substantially the form of a flat cone. An air exhaust pump 50, operated by an electric motor 51, is connected by a pipe 52 with the interior of the housing 48 near the upper end thereof and when in operation serves to exhaust the air from the receptacle 48 and to thereby draw the fluid from the receptacle 5 through the conduit 47 and cause the same to flow from that conduit over the cone-shaped spreader 49 in the form of a film which will drip from the edge of the spreader, while in film form, into the lower portion of the receptacle. By thus causing the fluids to flow in film form through the vacuum bubbles are largely eliminated and any air which may have been entrapped in the fluids is extracted therefrom and withdrawn from the re- 75

ceptacle. The receptacle 48 is connected at its lower end with a discharge pipe 53 which leads to a discharge pump 54, a portion only of which is shown but which is preferably a variable volume pump similar to the pump 37. In operation the discharge pump 54 is so adjusted as to volume that it will withdraw from the receptacle 48 exactly the same amount of fluid that is delivered by the manifold 17 to the receptacle 5.

It may sometimes happen that the fluids will be delivered to the receptacle 5 in improper proportions. For example, when the apparatus is first started in operation the fluids delivered to the manifold 17 may not be in proper proportion. I have therefore provided means for returning the fluid from the receptacle 48 to the receptacle 5 for further treatment. For this purpose the outlet of the discharge pump 54 is connected both with a discharge line 55, controlled by a valve 56 and with a return pipe 57 leading to the manifold 17 and controlled by a valve 58. By closing the valve 56 in the discharge line and opening the valve 58 in the return pipe the fluid which has been delivered to the receptacle 48 may be pumped back to the receptacle 5 and again passed over the centrifugal disk 9 in correct proportion to secure a proper blending thereof, or for any other purpose which makes recirculation of the fluid desirable. When the vacuum chamber 48 is not employed and the blending of the fluids is completed within the receptacle 5 the discharge pump would, of course, take the fluid from the receptacle 5 and the blended fluid could, when desired, be returned to the receptacle 5 by the pipe 57.

When the apparatus is to be placed in operation the exhaust pump 50 is first started to exhaust the air from the two receptacles, provided, of course, that the blending of the fluids is to be effected in a partial vacuum. The motor 40 is then started and when the disk 9 is revolving at high speed the motor 40 is started to place the several supply pumps in operation and the mingled fluids which are delivered to the centrifugal disk 9 will be blended as above described and delivered into the lower portion of the receptacle 5 from which they will be withdrawn through the conduit 41 to the vacuum chamber within the receptacle 48. When the blended fluid has accumulated in the vacuum chamber to the desired height, as indicated on the sight glass 59, the discharge pump 54 is started in operation and is so adjusted that it will withdraw the same amount of fluid that is delivered to the receptacle 5. In the event it is desired to recirculate the first portion of the fluid passing through the apparatus, to secure a more perfect blending thereof, the valve 56 in the discharge line 55 is closed and the valve 58 in the return line 57 opened. The discharge pump 54 is then started as soon as fluid begins to flow into the vacuum chamber and this fluid is withdrawn from that chamber and returned to the receptacle 5. When the recirculation has been continued for a length of time sufficient to secure the proper proportioning of the fluids the valve 58 is closed and the valve 56 opened and the discharge pump is stopped until the fluids have risen to the desired level in the vacuum chamber and the pump is then started. The apparatus may then continue to operate indefinitely so long as the fluids are supplied to the supply pipes 38.

In order that the operation of the apparatus within the receptacle 5 may be observed I have

provided in the top 6 of this receptacle a sight opening 60, closed by glass or other transparent material, and have also provided means, as shown at 61, for supporting an electric lamp within the upper portion of the receptacle, whereby sufficient illumination may be had to enable the mechanism and fluids to be viewed through the sight opening.

While I have described the preferred form of my method and have shown and described one form of apparatus for performing the same I wish it to be understood that I do not desire to be limited to the details thereof as various modifications may occur to a person skilled in the art.

Having now fully described my invention what I claim as new and desire to secure by Letters Patent, is:

1. In a mixing apparatus, a disk mounted for rotation in a substantially horizontal plane, said disk having an outer portion of its upper surface inclined upwardly and outwardly with relation to the plane of rotation of said disk and having an inner portion of said upper surface depressed to form an annular recess and merging into said inclined surface, means for delivering a fluid mass to said annular recess, means for rotating said disk at high speed to cause said mass to move from said recess over said inclined surface and to be discharged from said disk in the form of a continuous thin film, and a structure surrounding said disk and arranged in the path of the fluid discharged therefrom.

2. In a mixing apparatus, a disk mounted for rotation in a substantially horizontal plane, said disk having an outer portion of its upper surface inclined upwardly and outwardly with relation to the plane of rotation of said disk and having an inner portion of said upper surface depressed to form an annular recess and merging into said inclined surface, means for delivering a fluid mass to said annular recess, means for rotating said disk at high speed to cause said mass to move from said recess over said inclined surface and to be discharged from said disk in the form of a continuous thin film, a receptacle, and means for delivering said film to said receptacle without interrupting the continuity thereof.

3. In a mixing apparatus, a disk mounted for rotation in a substantially horizontal plane, said disk having an outer portion of its upper surface inclined upwardly and outwardly with relation to the plane of rotation of said disk and having an inner portion of said upper surface depressed to form an annular recess and merging into said inclined surface, means for delivering a fluid mass to said annular recess, means for rotating said disk at high speed to cause said mass to move from said recess over said inclined surface and to be discharged from said disk in the form of a continuous thin film, a receptacle having a wall surrounding said disk, and a deflector mounted between said disk and said wall and having a surface arranged in the path of said film at an acute angle thereto to deflect said continuous film downwardly against said wall.

4. In a mixing apparatus, a receptacle, a supporting structure arranged near the upper end of said receptacle, a shaft journaled in said structure, a disk having a hub rigidly secured to the lower end of said shaft, said disk having an outer portion of its upper surface inclined upwardly and outwardly with relation to the plane of rotation of said disk and having an inner portion of said upper surface depressed to form an annular recess about said hub and merging

gradually into said inclined surface, said supporting structure having an annular conduit extending about said shaft, and an annular flange extending downwardly about said hub into said recess in said disk and spaced from said hub to form a passageway, the wall of said annular conduit having openings to connect the same with said passageway, means for supplying fluid to said conduit and said disk, means for rotating said disk to cause said fluid to move outwardly in contact with said inclined surface and to be discharged from said disk in the form of a thin film, and means to deflect said film downwardly and cause the same to impinge against the wall 15 of said receptacle at an acute angle.

5. In a mixing apparatus, a receptacle, a supporting structure arranged near the upper end of said receptacle, a shaft journaled in said structure, a disk having a hub rigidly secured 20 to the lower end of said shaft, said disk having an outer portion of its upper surface inclined upwardly and outwardly with relation to the plane of rotation of said disk and having an inner portion of said upper surface depressed to 25 form an annular recess about said hub and merging gradually into said inclined surface, said supporting structure having an annular conduit extending about said shaft, an annular flange extending downwardly about said hub 30 into said recess in said disk and spaced from said hub to form a passageway, the wall of said annular conduit having openings to connect the same with said passageway, an annular member extending across the openings in the wall of said 35 annular conduit in spaced relation thereto and having its lower edge within and spaced from said annular flange to restrict and equalize the flow of fluid through said passageway, an annular guard slidably mounted on said flange with 40 its outer edge adjacent to the inclined surface of said disk, means for supplying fluid to said conduit and said disk, means for rotating said disk to cause said fluid to move outwardly in contact with said inclined surface and be discharged from said disk in the form of a thin 45 film, and means to deflect said film downwardly and cause the same to impinge against the wall of said receptacle at an acute angle.

6. In a mixing apparatus, a receptacle, a supporting structure arranged near the upper end of said receptacle, a shaft journaled in said structure, a disk having a hub rigidly secured to the lower end of said shaft, said disk having an outer portion of its upper surface inclined 55 upwardly and outwardly with relation to the plane of rotation of said disk and having an inner portion of said upper surface depressed to form an annular recess about said hub and merging gradually into said inclined surface, said supporting structure having an annular conduit extending about said shaft, an annular flange extending downwardly about said hub 60 into said recess in said disk and spaced from said hub to form a passageway, the wall of said annular conduit having openings to connect the same with said passageway, means for supplying fluid to said conduit and said disk, means for rotating said disk to cause said fluid to move outwardly 65 in contact with said inclined surface and to be discharged from said disk in the form of a thin film, a deflector ring mounted about and spaced from said disk and having an inclined lower surface in the path of the film discharged 70 from said disk to deflect said film downwardly 75

against the wall of said receptacle at an acute angle.

7. In a mixing apparatus, a sealed receptacle, a disk mounted in said receptacle for rotation in a substantially horizontal plane, means for delivering a plurality of fluids simultaneously to the upper surface of said disk near the axis thereof, means for rotating said disk to cause said fluids to move outwardly in contact with the upper surface thereof and to be discharged therefrom in the form of a continuous film, a deflector mounted about and spaced from said disk and having an inclined lower surface in the path of said film to deflect said film downwardly against the wall of said receptacle at an acute angle, a second sealed receptacle, a conduit leading from the lower portion of the first mentioned receptacle to the upper portion of said second receptacle, means for exhausting air from said second receptacle, and causing the fluid to flow 10 from the first mentioned receptacle to said second receptacle, and a spreader in the upper portion of said second receptacle to receive the fluid from said conduit and spread the same into a thin film. 15

8. In a mixing apparatus, a sealed receptacle, a disk mounted in said receptacle for rotation in a substantially horizontal plane, means for delivering a plurality of fluids simultaneously to the upper surface of said disk near the axis 20 thereof, means for rotating said disk to cause said fluids to move outwardly in contact with the upper surface thereof and to be discharged therefrom in the form of a continuous film, a deflector mounted about and spaced from said disk and having an inclined lower surface in the path of said film to deflect said film downwardly against the wall of said receptacle at an acute angle, a second sealed receptacle, a conduit leading from the lower portion of the first mentioned receptacle to the upper portion of said second receptacle, means for exhausting air from said second receptacle, and causing the fluid to flow 25 from the first mentioned receptacle to said second receptacle, a spreader in the upper portion of said second receptacle to receive the fluid from said conduit and spread the same into a thin film, and means for returning the fluid from said second receptacle to the disk in said first mentioned receptacle. 30

9. In a device for mixing a fluid mass, the combination of a rotatable member provided with an annular, material-supporting and conveying surface, a generating element of which has an appreciable axial component considerably smaller than its radial component, means for feeding the material to be mixed to the inner periphery of said annular surface in the form of a continuous film, and means adjacent the outer periphery of said annular surface for collecting the attenuated continuous film discharged therefrom, all of said means so arranged that said film is mechanically supported on one side only and that the continuity of said film is maintained. 35

10. In a device for mixing a fluid mass, the combination of a rotatable member provided with an annular, material-supporting and conveying surface, a generating element of which has an appreciable axial component considerably smaller than its radial component, means for feeding the material to be mixed to the inner periphery of said annular surface in the form of a continuous film, and means adjacent the outer periphery of said annular surface for 40

- collecting the attenuated continuous film discharged therefrom, said means including a stationary wall against which said continuous film is projected at an acute angle, all of said means so arranged that said film is mechanically supported on one side only and that the continuity of said film is maintained.
11. In a device for mixing a fluid mass, the combination of a rotatable member provided with an annular, material-supporting and conveying surface, a generating element of which has an appreciable axial component considerably smaller than its radial component, means for feeding the material to be mixed to the inner periphery of said annular surface in the form of a continuous film, and means adjacent the outer periphery of said annular surface for collecting the attenuated continuous film discharged therefrom, said means comprising an annular deflector adapted to deflect said attenuated continuous film at an acute angle against a stationary wall, all of said means so arranged that said film is mechanically supported on one side only and that the continuity of said film is maintained.
12. In a device for mixing a fluid mass, the combination of a rotatable member provided with an annular, material-supporting and conveying surface, a generating element of which has an appreciable axial component considerably smaller than its radial component, means for feeding the material to be mixed to the inner periphery of said annular surface in the form of a continuous film, and means adjacent the outer periphery of said annular surface for collecting the attenuated continuous film discharged therefrom, said means comprising an annular deflector adjustably supported with respect to the discharge periphery of said annular surface and adapted to deflect said film at an acute angle against a stationary wall, all of said means so arranged that said film is mechanically supported on one side only and that the continuity of said film is maintained.
13. In a device of the character described, the combination of a rotatable member provided with an annular material-supporting and conveying surface, means for impounding a quantity of the material to be treated centrally of said member and adapted to feed such material in the form of a continuous film onto the inner periphery of said surface, and means adjacent the outer periphery of said surface for collecting the attenuated continuous film, all of said means so arranged that said film is mechanically supported on one side only and that the continuity of said film is maintained.
14. In a device of the character described, the combination of a rotatable member provided with an annular material supporting and conveying surface, means for impounding a quantity of the material to be treated centrally of said member and adapted to feed such material in the form of a continuous film onto the inner periphery of said surface, said means comprising a baffle arranged centrally over said rotatable member with its outer periphery adjacent the inner periphery of said annular area, and means adjacent the outer periphery of said surface for collecting the attenuated continuous film, all of said means so arranged that said film is mechanically supported on one side only and that the continuity of said film is maintained.
15. In a device of the character described, the combination of a rotatable member provided with an annular, material-supporting and conveying surface, a generating element of which has an appreciable axial component considerably smaller than its radial component, means for feeding the material to be mixed to the inner periphery of said annular surface in the form of a continuous film, and means adjacent the outer periphery of said annular surface for collecting the attenuated continuous film, all of said means so arranged that said film is mechanically supported on one side only and that the continuity of said film is maintained.
16. In a device of the character described, the combination of a rotatable member provided with an annular material-supporting and conveying surface, means for impounding a quantity of the material to be treated centrally of said member and adapted to feed such material in the form of a continuous film onto the inner periphery of said surface, and means adjacent the outer periphery of said surface for collecting the attenuated continuous film, all of said means so arranged that said film is mechanically supported on one side only and that the continuity of said film is maintained.
17. In a device of the character described, the combination of a rotatable member provided with an annular material-supporting and conveying surface, means for impounding a quantity of the material to be treated centrally of said member, said means comprising a baffle member movably supported over the central portion of said member and adapted to float on the material being treated, the outer periphery of said baffle lying between the inner and outer peripheries of said annular surface, and means for driving said rotatable member.
18. The method of mixing a plurality of components at least one of which is a liquid which comprises the steps of maintaining an impounded quantity of such commingled materials centrally of a rotating member, radially displacing said impounded mass into a continuous film, centrifugally attenuating said continuous film, while mechanically supported on one side only, by means of said rotating member moving said film radially outwardly, and then collecting said film.
19. The method of mixing a plurality of components at least one of which is a liquid which comprises the steps of maintaining an impounded quantity of such commingled materials centrally of a rotating member, radially displacing said impounded mass into a continuous film, centrifugally attenuating said continuous film, while mechanically supported on one side only, by means of said rotating member moving said film radially outwardly, and then collecting said film by deflecting the same at an acute angle against a stationary wall.
20. The method of mixing a plurality of components at least one of which is a liquid which comprises the steps of maintaining an impounded quantity of such commingled materials centrally of a rotating member, radially displacing said impounded mass into a continuous film, centrifugally attenuating said continuous film by means of said rotating member moving said film radially and axially while mechanically supported on one side only, such axial displacement being relatively small with respect to such radial displacement, and then collecting said continuous film.
21. The method of mixing a plurality of com-

ponents at least one of which is a liquid which comprises the steps of maintaining an impounded quantity of such commingled materials centrally of a rotating member, radially displacing said 5 impounded mass into a continuous film, centrifugally attenuating said continuous film by means of said rotating member moving said film radially and axially while mechanically supported on one side only, such axial displacement being relatively small with respect to such radial displacement, and then collecting said continuous film by deflecting the same at an acute angle against 10 a stationary wall.

22. The method of mixing a plurality of components at least one of which is a liquid which comprises the steps of maintaining an impounded quantity of such commingled materials centrally of a rotating member, radially displacing said 5 impounded mass into a continuous film, centrifugally attenuating said continuous film, while mechanically supported on one side only, by means of said rotating member moving said film radially outwardly, and then collecting said film, the generation and collection of said film being accomplished in at least a partial vacuum. 10
